UNITED STATES PATENT OFFICE.

CHARLES L. WICKHAM, OF NEW YORK, N. Y., ASSIGNOR TO WESTERN ELECTRIC COMPANY, OF CHICAGO, ILLINOIS, A CORPORATION OF ILLINOIS.

SPLICING-TOOL.

SPECIFICATION forming part of Letters Patent No. 789,193, dated May 9, 1905.

Application filed April 27, 1903. Serial No. 154,448.

To all whom it may concern:

Be it known that I, CHARLES L. WICKHAM, a citizen of the United States, residing at New York, in the county of New York and State of New York, have invented a certain new and useful Improvement in Splicing - Tools, of which the following is a full, clear, concise, and exact description.

My invention relates to a splicing-tool; and its object is to provide a device by which two ends of paper tape, such as is used in insulating electric cables, may be quickly and effectively spliced together.

The tool which I have invented is capable of making a splice by simply closing its jaws upon the overlapped ends of the tape without further manipulation of the tape beyond a slight pull upon the two ends to set the splice. So far as I am aware, this is the first tool by which a splice can thus be made in one operation without further manipulation of the tape.

I will describe my invention by reference to the accompanying drawings, in which—

Figure 1 is a perspective view of my splicing-tool. Fig. 2 shows the jaws closed upon two overlapped ends of paper tape. Fig. 3 shows the jaws opened again with the paper sticking to the teeth of one of said jaws. Fig. 4 is a plan view of the jaw which carries the cutting-teeth. Fig. 5 is a longitudinal section of the opposed jaws. Fig. 6 shows the overlapped ends of the tape after they have been cut, with the tongues bent out or displaced. Fig. 7 is a similar view showing the tongues on one tape end interlocked with the tongues formed in the slots in the other tape end, and Fig. 8 shows the smooth side of the completed splice.

The same letters of reference are used to designate the same parts wherever they are shown.

The splicing-tool consists simply of two flat jaws *a b*, mounted in opposition upon the ends of suitable arms or handles *c c*, which are pivoted together at *d*. A spring *d'* may be provided to keep the jaws normally open. On one of the jaws *b* slanting teeth *b' b'* are pro-

vided, which are adapted to enter corresponding holes *a' a'* in the other jaw in such a way that the overlapped ends of the paper tape placed between said jaws will be given a series of cuts to form tongues, the tongues of one tape end being adapted to interlock with the slots left by the displacement of the tongues in the other tape end. The splice may be set by simply pulling the ends of the tape, because the teeth of the splicing-tool not only make the cuts necessary to form the interlocking tongues, but their slanting faces also bend out these tongues, as shown in Fig. 6, and enter the tongues of one tape end in the slots of the other.

The teeth may be given various forms; but the construction which I have found most satisfactory is that shown in Figs. 1, 3, and 5. As seen in plan the form of each tooth is rectangular, exactly fitting a rectangular slot in the opposing jaw. As seen in elevation, Fig. 5, the projecting portion of the tooth is in the form of a right-angled triangle, the hypotenuse whereof coöperates with the longitudinal edges of the slots in the upper jaw to form a shear. The cuts forming the sides of the tongues are made by these longitudinal shear edges. The cross-cut between the corresponding ends of the longitudinal cuts is formed by the projecting edge of the end of the tooth coöperating with the corresponding edge of the hole in the other jaw to form a shear. A V-shaped channel *b''* is preferably cut longitudinally in the top or face of each tooth, whereby sharp points are formed at the corners of the tooth to perforate the paper more easily. Said channels also form sharp beveled cutting edges, as shown. I preferably provide six teeth in a row, as shown, the height of the teeth being gradually increased from one end of the row to the other, so that all the teeth will not make the initial perforation at the same time. By this means the cutting operation may be performed more easily.

I have shown the jaws *a b* sharpened or brought to a point at one end, whereby the

superfluous end of one of the pieces of tape projecting beyond the end of the jaw *b* may be readily torn off to the shape indicated by dotted lines in Figs. 6 and 7, so as to make a 5 neat splice.

The operation of the tool will be readily understood. The ends of the tape to be spliced are overlapped and placed between the jaws, whereupon the jaws are closed together, as 10 shown in Fig. 2. This perforates both pieces of tape *e f* in such a way as to form a row of tongues *e' f'* therein and also bends these tongues up, as shown most clearly in Fig. 3, so that the tongues *e'* of the strip *e* are actually 15 entered in the slots formed by the cutting of the tongues *f'* in the strip *f*. The jaws being opened, the tape is disengaged therefrom and the splice set by simply pulling upon the tape end *e* in the direction indicated by the arrow in Fig. 3. In this way the tongues *e'* are interlocked with the slots in the tape *f*, forming the complete splice, as shown in Figs. 7 and 8.

Having thus described my invention, I 25 claim—

1. A splicing-tool for paper tape comprising two jaws mounted in opposition upon pivoted handles, one of said jaws having a series of angular holes cut clear through said jaw 30 and opening at the back thereof, the other jaw having a series of corresponding angular teeth coöperating with the edges of said holes to form shears, each of said teeth being triangular in elevation, forming a sharp cutting 35 edge at one end which first engages the tape, whereby free angularly-projecting tongues may be cut upon the overlapped ends of paper tape placed between said jaws, and the tongues on one tape end entered in the slots

formed by the displacement of the tongues of 40 the other tape end.

2. A tape-splicing tool comprising two opposed flat jaws *a b*, one of said jaws having a series of holes *a'* in its face and the other jaw having a corresponding series of teeth *b'* 45 adapted to enter said holes, the face of each tooth slanting upward from the surface of the jaw to the top of the tooth and having a groove or channel *b''* therein, whereby sharp beveled shear edges are formed adapted to form 50 angularly-projecting superposed tongues upon the overlapped tape ends placed between said jaws.

3. A tape-splicing tool comprising a pair of opposing flat jaws, one of said jaws having a 55 series of holes in the face thereof and the other jaw having a corresponding series of slanting teeth adapted to enter said holes, said teeth being of different heights, substantially as set forth.

4. A splicing-tool for paper tape comprising two opposed jaws adapted to be closed together upon the overlapped ends of the tape, one of said jaws having a series of holes in its face and the other jaw having a corresponding 65 series of teeth adapted to enter said holes and cut interlocking tongues and slots therein, said jaws being sharpened at their ends substantially as described, whereby the superfluous tape may be torn off to make a neat 70 splice.

In witness whereof I hereunto subscribe my name this 28th day of March, A. D. 1903.

CHARLES L. WICKHAM.
